(57) **CLAIM**

The ornamental design for a folding bracket, as shown and described.

DESCRIPTION

FIG. 1 is a top, front perspective view of the folding bracket; FIG. 2 is a bottom, rear perspective view of FIG. 1; FIG. 3 is a front view of FIG. 1; FIG. 4 is a rear view of FIG. 1; FIG. 5 is a left view of FIG. 1; FIG. 6 is a right view of FIG. 1; FIG. 7 is a top view of FIG. 1; FIG. 8 is a bottom view of FIG. 1; FIG. 9 is another top, front perspective of the folding bracket in a folded state; and, FIG. 10 is a partially enlarged view of FIG. 1. The broken lines shown on the drawings depict portions of the folding bracket that form no part of the claimed design.

1 Claim, 10 Drawing Sheets
